US00D867384S

(12) **United States Design Patent** (10) Patent No.: **US D867,384 S**
Siccardi et al. (45) Date of Patent: ** Nov. 19, 2019

(54) **DISPLAY SCREEN OR PORTION THEREOF WITH GRAPHICAL USER INTERFACE**

(71) Applicant: **Medacta International SA**, Castel San Pietro (CH)

(72) Inventors: **Francesco Siccardi**, Castel San Pietro (CH); **Gianluca Olgiati**, Castel San Pietro (CH); **Marco Cavagna**, Castel San Pietro (CH)

(73) Assignee: **MEDACTA INTERNATIONAL SA**, Castel San Pietro (CH)

(**) Term: **15 Years**

(21) Appl. No.: **29/656,294**

(22) Filed: **Jul. 11, 2018**

Related U.S. Application Data

(62) Division of application No. 29/591,398, filed on Jan. 19, 2017, now Pat. No. Des. 825,593.

(57) **CLAIM**

The ornamental design for a graphical user interface for a display screen or portion thereof with graphical user interface, as shown and described.

DESCRIPTION

The sole FIGURE is a front view of a display screen or portion thereof with graphical user interface, showing our new design.

The broken line showing of a display screen forms no part of the claimed design.
